GLASS BEVELING MACHINE

Anthony Macellaro and Anthony Tornese,
Brooklyn, N. Y.

Application October 1, 1938, Serial No. 232,752

2 Claims. (Cl. 51—101)

The invention here disclosed relates to the beveling of glass and like materials, such as used for mirrors and other purposes.

Objects of the invention are to provide a machine which will be capable of beveling practically any desired shapes, which will be capable of performing any one or any number of the various operations usually required, such as the "roughing", "smoothing", "polishing" and "roughing" operations, and which will be accurate and uniform in its action.

Additional objects and the novel features of construction, combinations and relations of parts by which the objects of the invention are attained are hereinafter set forth or will appear in the course of the following specification.

The drawings accompanying and forming part of the specification illustrate a practical commercial embodiment of the invention. The actual physical structure of the invention may be modified and changed in various respects all within the true intent and broad scope of the invention as hereinafter defined and claimed.

Fig. 1 is a broken part sectional front view of the machine with the parts in position for the first or what is ordinarily termed the roughing operation.

Fig. 2 is a broken plan view of the same.

Fig. 3 is a broken side elevation of the machine as viewed from the right in Fig. 1.

Fig. 4 is a broken vertical sectional view of the adjustable base construction as taken on substantially the plane of line 4—4 of Fig. 1.

Fig. 5 is a broken plan view showing the machine as set for the smoothing operation.

Fig. 6 is a left hand side view of the machine as it appears in Fig. 5.

Fig. 7 is a broken sectional detail of the hollow shaft which carries the suction chuck at one end and the templet or pattern cam at the opposite end.

The machine shown comprises a substantial base 10, carrying uprights 11, in which a shaft 12, is journalled in vertically adjustable bearings at 13. This shaft is driven as by belt pulley 14, and has mounted on it in longitudinally adjustable relationship at 15, a glass working wheel 16.

For the initial or roughing operation, a "carborundum" wheel may be employed, for the intermediate, smoothing operation a wheel of "aloxite" may be used and for the final polishing and roughing operations, a felt wheel may be used.

The glass is handled in the form of blanks 17, which have been cut to the desired outlines and these blanks are held and presented to the wheel by means of a suction chuck 18, having the same shape as the blank. This correspondence of shape enables the blank to be quickly placed and immediately accurately centered on the chuck.

The chuck is shown as adjustably and removably secured at 19, on one end of a hollow shaft 20, to the opposite end of which a suction pipe 21, is connected by a swivel coupling 22. By means of a hand valve 23, the suction can be turned on and off to hold or to release the blank. The chuck may be faced with a layer of cork or other suitable cushioning material 24, and one or more suction passages such as indicated at 25, may be provided in this facing, such passage or passages opening to the interior of the hollow supporting shaft.

For the roughing and polishing operations, it is usually considered best to present the glass flatwise to the wheel and for the intermediate smoothing operation, best results are usually obtained by presenting the glass edgewise to the wheel. To meet such requirements, the chuck shaft in the present machine is mounted so that it may be positioned either vertically, with the chuck at the upper end of it in a horizontal plane as in Figs. 1, 2 and 3, or be positioned horizontally with the chuck in a vertical plane and inclined to the axis of the wheel, as in Figs. 5 and 6.

The form of mounting for such purposes is shown as a bracket 26, having side arms carrying bearings 27, at one end for the chuck shaft and carrying bearings 28, at the opposite end engaged over a supporting spindle 29.

The spindle 29 is shown in Fig. 4 as having its lower end extending through a transverse bore in a supporting hub 30, and aligning openings in a surrounding sleeve 31. An annular shoulder 32, enables the spindle to be stepped in this relation. The supporting hub 30, is shown as having a screw-threaded stud portion 33, extending through slot 34, in an upright supporting bracket 35. A nut 36, engaged on this stud serves to draw the hub toward the back of this bracket and in this action to cause the spindle to force the sleeve 31, against the face of the bracket, thus to clamp the spindle firmly against movement in any direction.

A vertical screw 37, is indicated as rotatably mounted in the supporting bracket 35, and as

having screw-threaded engagement with the stud portion 33, of hub 30. Upon loosening clamp nut 36, this vertical screw may be employed to raise or lower the spindle supporting hub 30, 5 and upon removal of this vertical adjusting screw, which may be easily accomplished after taking off the screw secured cap 38, the hub 30 and sleeve 31, may be turned to lower the spindle 29 into the horizontal relation illustrated 10 in Figs. 5 and 6.

Operation on the work is definitely and accurately controlled by means of a templet, in the nature of a profile cam 39, adjustably and removably secured at 40, on the hollow chuck shaft 15 20, in a position to engage a roll 41, on the end of an arm 42, projecting from and fixedly secured to the spindle supporting hub 30 at 43, Figs. 3 and 4.

By means of bearings 28, the bracket or frame 20 26, which carries the combined chuck and cam shaft, is capable of swinging movement about the axis of the supporting spindle 29, and is urged toward the wheel by a weight 44, on the end of a flexible connection 45, extending up over 25 a pulley 46, at the side of the machine to a point of engagement with the free end of the frame at 47.

Rotation of the chuck shaft to cause the cam or pattern plate to ride over the position determining roll 41, is effected in the illustration by a chain 48, extending from sprocket gear 49, to a sprocket gear 50, removably and adjustably secured on the chuck shaft at 51. The sprocket gear 49, as shown more fully in Fig. 4, is keyed to and thus in effect forms part of a worm gear 52, rotatably mounted on the supporting spindle 29, and said worm gear is engaged by a worm 53, on a shaft 54, driven from the main shaft 12.

In the machine as set up for the roughing and polishing operations, as shown in Figs. 1 to 4, the worm shaft 54, may be substantially parallel with shaft 12, and hence be driven direct by a belt 55, from pulley 56, on shaft 12, to pulley 57, on shaft 54.

When the machine is set for the smoothing operations, Figs. 5 and 6, with the shaft 54, out of parallel with shaft 12, the drive may be effected by providing shaft 54, with an extension 54a, carrying the pulley 57, coupled by a universal joint 58, and supported in a journal bearing 59, bolted down on the base 10.

In shifting from the horizontal position of the chuck supporting bracket, Fig. 1, to the vertical position shown in Fig. 6, it is necessary to shift the worm shaft 54, in the bracket, so that in the new relation, it will occupy a horizontal or nearly horizontal position. This is provided for in the illustration by journaling the worm shaft in the spaced arms 60, of a bracket 61, 55 60 having a hub portion engaged on the supporting spindle and adjustably secured in desired angular relation thereon by a set screw 62.

The spindle supporting bracket 35 is shown 65 in Fig. 4 as secured by bolt 63, in position rotatably adjustable about a vertical axis. This bolt is set in a slide 64, which can be advanced or retracted by feed screw 65, on a head 66, rotatably held at 67, on a sub-base 68. The latter 70 is indicated as adjustably secured by clamps 69, in a slotted way 70, in the main base plate 10. The several adjustments thus provided enable the entire chuck and pattern follower assembly 75 being bodily adjusted toward and away from the wheel shaft and any desired angular adjustments

to be made about a vertical axis. Thus any required take-up for wear of the wheel or other parts, or to suit different angles of bevel can be readily effected.

The machine can be easily changed from the position first shown for roughing and polishing operations, to the second position shown in Figs. 5 and 6 for smoothing operations or vice versa. In commercial large scale production, a number of the machines may be employed, with some of them set for certain operations and others set for the other necessary operations, the chucks and the cams of the different machines being counter-parts or alike to the extent of effecting successive operations on the same shape blanks. 10

The swinging frame which carries the chuck and pattern cam is shown provided with a projecting handle 71, by which the frame may be drawn back from the wheel at any time and if desired, means may be provided for holding the frame in retracted position, such as a properly located hook or the like. 15

By using appropriately shaped chucks and templets, the glass for mirrors or other purposes may be ground, smoothed, polished and rouged in practically any desired shapes and in only three steps or stages, as disclosed. By feeding the work smoothly and evenly to the wheel, the bevel produced is accurate and uniform, following as exactly as may be desired the contour 20 25 30 of the piece.

To facilitate accurate placing of the work on the chuck, some means may be provided for stopping the rotative movement of the chuck when the frame is swung back from the wheel. 35 In the present illustration, a belt shifter is shown at 72, Figs. 1, 2 and 3, projecting from the upper hub 28, of the swinging frame and adapted to throw the belt 55, from the fast pulley 57, over onto the loose pulley 73, as the frame is swung outward, away from the wheel. This belt shifter is indicated as removably attached to the swinging frame at 74, so that it may be taken off when the frame is turned around into the vertical position, Figs. 5 and 6, and in the latter position also, if desired, an automatic belt shifter or other means may be employed for throwing the chuck rotating means out of operation when the frame is shifted to the non-working position. 40 45

What is claimed is:

1. A glass beveling machine, comprising a substantially horizontally journaled shaft, a glass working wheel on said shaft, a support mounted for angular adjustment about a substantially horizontal axis and means for securing said support in different positions of angular adjustment, a spindle carried by said support and adapted to be rigidly held thereby in substantially horizontal or in substantially vertical position, a bracket mounted on said spindle, means for securing said bracket in different angular relations about said spindle, a shaft journaled in said angularly adjustable bracket spaced from and substantially at right angles to the axis of said spindle, a worm on said shaft, a worm gear journaled on the spindle in opposition to said worm and engaged thereby, drive connections from the substantially horizontal glass working wheel shaft to said worm shaft, a frame journaled to swing on said spindle, a tubular shaft journaled to rotate in the free swinging end of said frame, in substantial parallelism with said rigid supporting spindle, a glass blank holding suction chuck removably mounted on one end of said hollow shaft, swivelled suction connections 55 60 65 on the opposite end of said hollow shaft, a pattern cam removably mounted on said latter end of said hollow shaft an abutment for said cam carried by said angularly adjustable support and drive gearing from said worm gear journalled on the spindle to said hollow chuck shaft journalled in the swinging frame.

2. A glass beveling machine, comprising a substantially horizontally journalled shaft, a glass working wheel on said shaft, a support mounted for angular adjustment about a substantially horizontal axis and means for securing said support in different positions of angular adjustment, a spindle carried by said support and adapted to be rigidly held thereby in substantially horizontal or in substantially vertical position, a bracket mounted on said spindle, means for securing said bracket in different angular relations about said spindle, a shaft journalled in said angularly adjustable bracket spaced from and substantially at right angles to the axis of said spindle, a worm on said shaft, a worm gear journalled on the spindle in opposition to said worm

and engaged thereby, drive connections from the substantially horizontal glass working wheel shaft to said worm shaft, a frame journalled to swing on said spindle, a tubular shaft journalled to rotate in the free swinging end of said frame, in substantial parallelism with said rigid supporting spindle, a glass blank holding suction chuck removably mounted on one end of said hollow shaft, swivelled suction connections on the opposite end of said hollow shaft, a pattern cam removably mounted on said latter end of said hollow shaft an abutment for said cam carried by said angularly adjustable support and drive gearing from said worm gear journalled on the spindle to said hollow chuck shaft journalled in the swinging frame, said drive gearing including a sprocket gear connected with said worm gear, a sprocket gear removably secured on the hollow chuck carrying shaft and a chain connecting said sprocket gears.
